RELAXATION OSCILLATION GENERATOR

Kurt Schlesinger, Berlin, Germany

Application September 16, 1933, Serial No. 689,760
In Germany September 27, 1932

6 Claims. (Cl. 250—36)

When employing glow lamps, and more particularly gas-filled glow lamps, in the known relaxation oscillation generators, the first part of the discharge takes place so rapidly that the 5 return line on the television screen is not visible. On the other hand the discharge, on the final part of the discharge curve, shortly before extinguishing commences to take place, proceeds relatively slowly. This part of the return line is 10 accordingly visible on the screen of the Braun tube.

The subject matter of the invention is a method of and also an arrangement for enabling this disadvantage to be avoided. The invention will 15 be best understood with reference to the accompanying drawing, in which Fig. 1 shows the scanned picture area with the course of the return line, while Figs. 2 and 3 show exemplary embodiments of the invention for removing the 20 visible portion of the return line from the picture area.

In Fig. 1 the upper part of the return line commences with a sharp bend at 1 and is completely invisible up to the point 2. The lower 25 part of the return line owing to the slower wandering velocity over the picture screen is thickened, and is visible in a disturbing fashion in the image.

According to the invention, the anode of the 30 glow lamp 3, after commencement of the ignition, receives a suitable counter-potential, which is greater than the anode potential at that particular time. In this manner this potential at the time remains at the condenser, so that the 35 return line breaks off at the point of commencement of the counter-potential, and accordingly disappears entirely from the image.

An arrangement with which this method is 40 capable of being performed is shown diagrammatically in Fig. 2.

In this figure, 3 is a glow lamp, which is preferably operated with a grid of suitable constant, negative bias, and 5 a condenser, which is charged in the known fashion by the battery 6 45 over the resistance 4. To the charging circuit there is connected a power amplifier 7 with wattless input. In the anode lead of the amplifier 7 there is provided a retarding member, which consists, for example, of the resistance 8 and the 50 condenser 9, and the primary winding of a step down high-frequency transformer 10. The secondary winding of this transformer, which winding is preferably constructed with very low high-frequency impedance, and which transformer 55 may be bridged by a small condenser 11, is con-

nected in series with the discharge circuit. The operation of the arrangement is as follows:

Whereas upon the charging of the tilting condenser 5 the discharge tube 3 is blocked by its control grid in respect of all anode potentials 5 occurring, and the high-frequency transformer 10, therefore, is also ineffective, upon the discharge there is provided in the anode circuit of the connected amplifier tube 7 a high-frequency impulse, which is transmitted very well by the 10 selective transformer. In the retarding member 8, 9 there is adjusted a delay of such extent as corresponds with the invisible branch of the return line 1, 2 in Fig. 1. It is not until this period has elapsed that the high-frequency impulse wave reaches the primary winding of 10, and produces in the secondary winding a potential impulse, the value of which is at least equal to the particular relaxation condenser potential 15 at the moment, and preferably is greater than the remaining potential, and the phase of which for the first moment of the condenser potential 20 is oppositely directed. With suitable selection of this counter-potential it may readily be accomplished that the duration of the potential-less condition at the anode of the glow tube suffices 25 for a complete de-ionization of the arc. The subsequent disposal of the secondary winding of the transformer is accordingly unimportant, and possible oscillation effects thereof are without 30 harm, as the discharge tube, owing to the occurrence of the grid effect, is again blocked for 35 all anode potentials.

An additional form of embodiment of the idea 40 according to the invention is illustrated diagrammatically in Fig. 3. The counter-impulse which blocks the discharge is not derived by reaction 45 from the discharge operation itself, but from the synchronization potential, for example a signal potential. This potential is indicated in Fig. 3 by the generator 12. For television purposes 50 this potential is necessary in any case for the operation, and is supplied by the television receiving apparatus to the relaxation oscillation system. Alternatively, this potential may also 55 be taken from the supply potential at the terminals of the condenser 5. The potential 12 is first conducted over a phase shifter 13, which produces its correct chronological relation to the discharge phase. It then passes to a suitable amplifier 15. This amplifier must be in a position to produce at the impedance resistance 16 connected 60 in the discharge circuit, for example a small coil, a potential of small amount, which is sufficient 65 to make the anode potential at the glow dis- 70

charge tube 3 for a sufficient length of time equal to zero or negative. The form of the curve after this point is unimportant. After the amplifier 15 there is preferably connected in series a high-pass filter 17, the reactance of which for the useful frequency of the relaxation oscillation is extremely high.

Naturally, it is quite possible, without departing from the idea according to the invention, also 10 to set forth other circuits for carrying out the method in the invention, which systems permit of performance of the method in simple fashion.

In the method according to the invention the charging condenser is on each occasion dis- 15 charged, not down to zero, but merely down to the potential corresponding with the point 2 of the return line. This loss of potential, however, may be counter-balanced without difficulty by increasing the working potential. The method 20 according to the invention enables television images to be produced, which are completely free of a visible return line.

I claim:

1. A generator for producing relaxation oscil- 25 lations comprising a unidirectional source of potential, a charging condenser and a charging resistance in series, a glow discharge device across said charging condenser, an amplifier means having input and output, said input being connected 30 across said device and means connected to said output for applying a potential across said condenser and device counter-acting the condenser potential during a part of the discharge period of said condenser for preventing a complete dis- 35 charge of said condenser by said glow discharge device.

2. A generator for producing relaxation oscil- 40 lations comprising a unidirectional source of potential, a charging condenser and a charging resistance in series, a glow discharge device across said charging condenser, an amplifier having input and output, said input being connected across said device and means connected in said output for feeding back a potential across said condenser 45 and device during a part of the discharge period of said condenser for preventing a complete discharge of said condenser by said glow discharge device.

3. A generator for producing relaxation oscil- 50 lations comprising a unidirectional source of potential, a charging condenser and a charging resistance in series, a glow discharge device across said charging condenser, a high frequency step-down transformer, the secondary thereof being 55 connected in series with said glow discharge device across said condenser, an amplifier stage having input and output circuits, the input circuit being connected across said device, the primary of said transformer being connected in the output circuit of said amplifier stage and phase-retarding means being connected in said output circuit.

4. A generator for producing relaxation oscil- 5 lations comprising a unidirectional source of potential, a charging condenser and a charging resistance in series, a glow discharge device across said charging condenser, a high frequency step-down transformer, the secondary thereof being connected in series with said glow discharge device across said condenser, an amplifier stage having input and output circuits, the input circuit being connected across said device, 10 the primary of said transformer being connected in the output circuit of said amplifier stage and phase-retarding means comprising a second resistor and a second condenser connected in said anode circuit, said high frequency step-down transformer having a proportion of windings and said phase retarding means being so dimensioned as to generate a potential counter-acting the condenser potential at least to full extent during a part of the discharge period of said 15 charging condenser for preventing complete discharge of said condenser by said discharge device during said part of the discharge period.

5. A generator for producing relaxation oscil- 20 lations comprising a unidirectional source of potential, a charging condenser and a charging resistance in series, a grid controlled glow discharge device having cathode and anode electrodes, said electrodes being connected across said charging condenser, means for applying a synchronizing potential to the grid of said discharge device, means for generating an additional potential controller by said synchronizing potential, means for applying said additional potential to counter-act the condenser potential 25 during a part of the discharge period of said condenser for preventing a complete discharge of said condenser by said glow discharge device.

6. A generator for producing relaxation oscil- 30 lations comprising a unidirectional source of potential, a charging condenser and a charging resistance in series, a grid controlled glow discharge device having cathode and anode electrodes, said electrodes being connected across said condenser, an amplifier having input and output, a phase shifter, means for applying a synchronizing potential to the grid of said discharge device and to the input of said amplifier through said phase shifter, an impedance connected in series with the electrodes of said discharge device and said charging condenser, a high frequency filter, said impedance and filter being connected in series in the output circuit of said amplifier, said impedance withholding said synchronizing frequency from said condenser, 40 thus generating an additional potential derived from said synchronizing potential, said additional potential counter-acting the condenser potential during a part of the discharge period of said condenser for preventing a complete discharge of 45 said condenser by said glow discharge device.
